MACHINE FOR SHAPING CARDBOARD ARTICLES

Edwin H. Newton, Kansas City, Mo., assignor to
National Paper Box Co., Kansas City, Mo., a
corporation of Missouri

Application September 18, 1933, Serial No. 689,948

12 Claims. (Cl. 93—1)

This invention relates to a machine for shaping cardboard articles, such as the cardboard shields employed in connection with wire clothes hangers and has for its principal objects to provide for continuous high speed shaping of cardboard blanks whereby they receive a permanent curvature and set, to provide for automatically glazing the outer surfaces of the articles incidental to the shaping thereof, and to provide for automatically printing the articles upon their discharge from the machine.

In accomplishing these and other objects of the invention, I have provided improved details of structure, the preferred form of which is illustrated in the accompanying drawings, wherein:

Fig. 1 is a perspective view of a cardboard shaping machine constructed in accordance with my invention.

Fig. 2 is an enlarged longitudinal vertical section through the machine.

Fig. 3 is a plan view of the machine.

Fig. 4 is an enlarged detail fragmentary perspective view of a portion of the machine, particularly illustrating one of the sets of ironing disks or rollers, the disks or rollers being shown in section to better illustrate the construction.

Fig. 5 is an enlarged cross-sectional view through the machine on the line 5—5, Fig. 3.

Fig. 6 is a cross-section through the ironing track on the line 6—6, Fig. 2.

Fig. 7 is an enlarged detail perspective view of the feeding apparatus for delivering the blanks for consecutive passage through the machine.

Fig. 8 is a cross-sectional view through the machine on the line 8—8, Fig. 2.

Fig. 9 is a perspective view of one of the cardboard blanks.

Fig. 10 is a similar perspective view of the cardboard blank illustrating the shape imparted thereto after passing through the machine.

Referring more in detail to the drawings:

1 designates a table or supporting frame for the machine which in the illustrated instance includes a horizontal rectangular shaped top 2 of sufficient length to mount the shaping apparatus and which is supported by legs 3 located at the corners thereof, as illustrated in Fig. 1.

Supported upon one end of the table on spaced vertical posts 4 and 5 is a plate 6 having a horizontal portion 7 and an upwardly inclined rearwardly extending portion 8 forming a support for a plurality of cardboard blanks 9 that are to be delivered through the machine.

55 The posts 4 and 5 preferably include rods hav-

ing threaded upper ends 10 projecting through openings in the horizontal portion 7 of the plate, and carry nuts 11 and 12 for engaging opposite sides thereof whereby the plate may be adjusted vertically relatively to the shaping rollers, later described.

Fixed to the upper face of the inclined portion 8 are spaced angles 13 and 14 arranged so that the vertical legs 15 and 16 thereof form guides for retaining the blanks 9 in stacked relation preparatory to their delivery into the machine.

In order to feed the blanks from the stack, I provide a feed roller 17 and a counter feed roller 18 that are supported above and below the plate portions 7 and 8 respectively, the feed roller 17 being fixed to a shaft 19 that is rotatably mounted in arms 20 and 21 carried by brackets 22 and 23 and by the upper ends of the posts 4 and 5, as best illustrated in Figs. 1 and 7.

The roller 18 is mounted on the shaft 24 having its ends rotatably mounted in angle clips 25 depending from the lower face of the plate 7 at a point directly below the shaft 19. The roller 17 is preferably provided with a gripping surface 26 for contacting the ends of the blanks supported by the plate portion 8 and which are also contacted by the roller 18 through a rectangular shaped opening 27, Figs. 2 and 7, whereby the blanks are individually drawn from the stack and delivered across the plate portion 7 to be engaged by forming and shaping rollers 28 and 29.

In order to regulate the withdrawal of the blanks from the stack and to effect their individual feed by the feed rollers 17 and 18, I provide a feed regulator 30 including a channel shaped arm 31 that is pivotally mounted between ears 32 and 33 carried on the lower side of the plate portion 8 at opposite sides of the opening 27, as best illustrated in Fig. 7.

The arm 31 is pivotally connected to the ears 40 by pins 34 located substantially midway of the length thereof to provide free opposite ends 35 and 36. Fixed to the end 36 of the arm and adapted to yieldingly engage the periphery of the feed roller 17 is a flexible strip 37, the pressure of the strip 37 against the roller 17 being adjusted by a set screw 38 which is threadedly mounted in an opening 39 in the end 35 of the arm 31 and which is adapted to engage against the plate 8 to adjust the relative position of the arm and pressure of the strip 37.

The set screw 38 is retained in adjusted position by a lock nut 40 threaded on the screw and engaging against the arm 31, as illustrated in Fig. 2.

Cooperating with the feed rollers 17 and 18 is an idler roller 41 supported above the plate portion 7 to retain the ends of the blanks in contact therewith so that they are delivered directly between the forming rollers 28 and 29, the roller 41 being carried on a bracket 42 depending from the arm 21.

The forming and shaping roller 28 includes a flat disk having its periphery 43 of semicircular cross-section to impart a semicircular curvature to the blanks. The complementary roller 29 is of smaller diameter and is provided with a concave periphery 44 conforming to the periphery of the roller 28.

15 The roller 28 is mounted on a shaft 45 having its ends 46 and 47 rotatably mounted in bearings 48 and 49 carried by the brackets 22 and 23, previously described.

20 The roller 29 is fixed to a shaft 50 that is rotatably mounted in a recess 51 at one end of an ironing block 52 that is mounted on the table in alignment with the feed rollers. The ironing block is also provided with a longitudinal groove 53 in its upper face conforming in shape to the curvature imparted to the blanks by the rollers 28 and 29.

25 The axes of the shafts 45 and 50 are located at an elevation above the table so that the contacting peripheries of the forming rollers are in substantial alignment with the upper surface of the plate 7 and the groove 53.

In order to drive the rollers 28 and 29, the end 47 of the shaft 45 projects from the bearings 49 to mount a drive pulley 54 which is driven by a belt 55 operating over the drive pulley 56 of a suitable electric motor 57 that is carried below the table 2 as best illustrated in Fig. 1. The opposite end of the shaft 45 projects from the bearing 48 and carries a sprocket 58 aligning with a similar sprocket 59 on the shaft 19 carrying the feed roller 17, the sprocket 59 being driven from the sprocket 58 by a chain 60.

30 To heat the ironing block 52, the sides thereof are equipped with suitable electric heaters 61 and 62 which are connected to a source of current supply through conductors 63 and 64.

35 Extending from the delivery end 65 of the ironing block is an inverted channel shaped guide supporting member 66 that is carried above the table 2 in alignment with the groove in the ironing block by spaced pairs of brackets 67 and 68 having their upper ends fixed to the depending flanges 69 of the channel member and their lower ends fixed to the table top 2, as best illustrated in Fig. 8.

40 Mounted on the upper face of the web 70 of the channel member 66 are spaced angle members 71 and 72 having their horizontal legs lying flatly against the channel 66 and their vertical legs 73 and 74 forming guides for the cardboard articles to retain them in guided relation with pairs of ironing rollers 75, 76 and 77 which cooperate with rollers 78, 79 and 80.

45 The rollers 75, 76 and 77 are similar in shape to the roller 28 and are mounted on shafts 81 that are rotatably carried in bracket plates 82 and 83 projecting upwardly from the flanges 69 of the channel member 66, as best illustrated in Fig. 8, 50 while the lower rollers 78, 79 and 80, similar in shape to the roller 29 are mounted on shafts 84 that are positioned in notches 85 and 86 formed in the depending flanges of the channel and in the lower ends of the bracket plates 82 and 83, 55 Fig. 4, so that the upper portions of these rollers

may project through slots in the body portion of the channel 66 (Fig. 2).

To retain the periphery of the rollers 78, 79 and 80 in yielding contact with the rollers 75, 76 and 77, the shafts 84 are carried in bearing sleeves 87 and 88 fixed to the arms 89 of crank levers 90 which are pivotally mounted in bearing openings 91 formed in the depending flanges of the channel member, and have lever arms 92 extending rearwardly of the machine in a direction opposite to the arms 89 and which are yieldingly anchored to the table top 2 by coil springs 93 having one end fixed to the arm 92 and opposite ends to hooks 94 on the table.

10 It is thus apparent that the springs 93 through 15 the arms 92 and 89 of the crank levers retain the lower rollers in yielding contact with the peripheries of the upper ironing rollers.

15 The guide track is also heated from electric heaters 95 which are suspendingly supported 20 from the lower face of the channel member 66 by insulated posts 96, Fig. 8.

20 To drive the ironing rollers 75, 76 and 77, the shaft 45 is provided with a sprocket wheel 97 located thereon between the bearing 49 and the 25 pulley 54 and which actuates a chain 98 operating over a sprocket wheel 99 on the projecting end of the shaft for the ironing roller 75 to actuate the ironing roller 75, its complementary roller 78 being driven through gears 100 and 101 fixed 30 to the opposite end of the shaft 81 and to a projecting end of the shaft 84, as best illustrated in Fig. 4.

25 The ironing rollers 76, 79 and 77, 80 are driven by a chain 102 operating over a sprocket 103 on 35 the shaft of the roller 75 and over sprockets 104 and 105 on the shafts of the rollers 76 and 77.

30 The rollers 79 and 80 are driven from the shafts of the rollers 76 and 77 by sets of gears 106 and 107 similar to the gears 100 and 101, 40 previously described.

35 In order to tension the chains, I provide tensioning rollers 108 for the chain 98 and 109 for the chain 102, the tensioning roller 108 being rotatably mounted on a bracket 110 extending 45 upwardly from the table top 2 and the roller 109 being fixed to an arm 111 pivotally mounted on the channel member 66.

40 The roller 109 is yieldingly retained in contact with the chain 102 by a coil spring 112 having 50 one end fixed to the free end of a lever 111 and its opposite end to a pin 113 projecting from the sides of the ironing block.

45 In order to prevent the ends of the blanks from curving upwardly away from the guides, the 55 side edges of the groove in the ironing block and the vertical flanges 73 and 74 of the guide track are provided with inwardly extending flanges 114 and 115 to form stops for engaging the side edges of the blanks when they are bent to form as later 60 described.

50 In order to print formed articles, the discharge end of the channel iron 66 is provided with a pair of brackets 116 and 117 having upwardly extending arms 118 and 119 between which is rotatably 65 mounted a printing roller 120 and an inking roller 121 which contacts with the periphery of the printing roller. The periphery of the printing roller carrying type 122 is mounted so as to engage the blanks as they are delivered from the 70 machine. The upper ends of the arms 118 and 119 carry a reservoir 123 for containing a printing fluid which is dripped through a nozzle 124 onto the inking roller.

75 The blanks for which the illustrated machine 75

is constructed are best illustrated in Figs. 9 and 10 and are shown as to include a flat strip "A" having notched ends "B" adapted to engage the arms of a suit hanger to retain the strip on the pants bar of the hanger.

After the blank is delivered through the machine, it is formed in a trough shape, as illustrated in Fig. 10, so as to provide an extended rounded surface.

10. The machine may be enclosed by a housing 126, Fig. 8, to form a guard over the driving mechanism and to retain the heat of the heating elements.

In using a machine constructed and assembled 15 as described, the blanks are first tempered by treating them with a suitable fluid to render them pliable. The blanks are then stacked on the plate portion 8 between the guides 15 and 16 with the ends thereof fanned out, as clearly illustrated 20 in Fig. 2, so that the topmost blank engages between the periphery of the roller 17 and the feed regulating strip 37.

When the machine is started, the operation of 25 the feed roller causes the first blank to be drawn across the table portion 7 onto the roller 18 from where it is discharged between the forming and shaping rollers 28 and 29 to be shaped thereby as shown in Fig. 10.

As the blanks are delivered across the ironing 30 block, heat imparted to the block from the electric heaters tends to dry the blanks and cause them to take on an initial set so that they are retained in the shape which has been imparted to them. The blanks will continue their travel 35 through the guide-way formed between angles 71 and 72 where the ironing rollers continue the ironing and drying of the blanks. At the time of their discharge from the rollers 77 and 80, they are completely dried and passed to the printing 40 roller where suitable indicia or advertisements may be applied.

As soon as the first blank has been delivered 45 from the stack, the periphery of the feed roller engages the end of the next blank to cause its withdrawal and discharge into the machine.

From the foregoing, it is apparent that I have 50 provided a machine of simple construction, which is well adapted to the forming and shaping of cardboard articles, and which is capable of high speed operation.

What I claim and desire to secure by Letters Patent is:

1. In a machine of the character described, a support, means on the support for retaining a 55 stack of blanks, shaping rollers, means for mounting the shaping rollers on the support in receiving relation with the blank supporting means, an ironing member having a shaped track conforming to the shape imparted to the blanks 60 by said shaping rollers, means for individually feeding the blanks from the stack through the shaping rollers to shape the blanks, and means for moving said blanks over the track over said ironing member.

65. 2. In a machine of the character described, a support, means on the support for retaining a stack of blanks, blank shaping means on the support in receiving relation with the blank supporting means, blank ironing means on the support in receiving relation with said shaping means, means individually feeding the blanks from the stack through the shaping means to shape the blanks, and means for advancing the blanks across said ironing means.

70. 3. In a machine of the character described, a

support, means on the support for retaining a stack of blanks, means for individually withdrawing blanks from the stack, blank shaping means on the support in the path of the blanks withdrawn from the stack, blank ironing means on the support for receiving the blanks from said shaping means, means for advancing the blanks across said ironing means, and means for heating the blank ironing means.

4. In a machine of the character described, a support, means on the support for retaining a stack of blanks, a guide track on the support, means carried by the support for individually feeding blanks from the stack to said guide track, a series of shaping rollers associated with the 15 guide track for advancing and shaping the blanks, and means for heating the guide track.

5. In a machine of the character described, a support, means for retaining a stack of blanks on the support, an ironing block having a shaped 20 guide groove, means associated with the stack retaining means for individually feeding the blanks from the stack to the groove in said ironing block, shaping rollers associated with the ironing block for shaping the blanks to conform 25 with the shape of the guide groove in the block, means for heating the ironing block, and means for advancing the blanks.

6. In a machine of the character described, a support, means for retaining a stack of blanks 30 on the support, an ironing block having a guide groove, means associated with the stack retaining means for individually feeding the blanks from the stack to the groove in said ironing block, shaping rollers associated with the ironing block 35 for shaping the blanks to conform with the guide groove in the block, means for heating the ironing block, means for advancing the blanks, and means forming a continuation of said ironing block for retaining heat on the blanks.

7. In a machine of the character described, a support, means for retaining a stack of blanks on the support, an ironing block, means associated with the stack retaining means for individually feeding the blanks from the stack 45 across the ironing block, shaping rollers associated with the ironing block for shaping the blanks, means for heating the ironing block, a guide track mounted on the support in alignment with the ironing block, a series of ironing rollers 50 associated with the guide track and conforming in shape to the shaping rollers to advance the blanks through the guide track, and means for heating the guide track.

8. In a machine of the character described, 55 shaping and ironing couples successively engageable with blanks to be formed and operable to advance the blanks simultaneously with shaping and ironing of the blanks, means for feeding individual blanks to the shaping and ironing 60 couples in successive order, and means for heating a member of the ironing couple.

9. In a machine of the character described, 65 shaping and ironing couples successively engageable with blanks to be formed and operable to advance the blanks simultaneously with shaping and ironing of the blanks, means for feeding individual blanks to the shaping and ironing couples in successive order, and means for heating the 70 blanks adjacent the shaping couple.

10. In a machine of the character described, 75 shaping and ironing couples successively engageable with blanks to be formed and operable to advance the blanks simultaneously with shaping

- and ironing of the blanks, means for feeding individual blanks to the shaping and ironing couples in successive order, and means for heating the blanks adjacent the ironing couple.
- 5 11. In a machine of the character described, shaping and ironing couples successively engageable with blanks to be formed and operable to advance the blanks simultaneously with shaping and ironing of the blanks, means for feeding individual blanks to the shaping and ironing couples in successive order, means for guiding the blanks adjacent said couples, and means for heating the blanks while in the guides.
- 10 12. In a machine of the character described, an ironing block including a shaped guide track, means for heating the block to effect set of blanks passed over the guide track, a guide track forming a continuation of the track in the ironing block, means for heating the last named guide track, 5 means for initially shaping the blank to conform with the first guide track, and means for pressing a blank to the guide track forming a continuation of the track in the ironing block, the shaping and pressing means acting to advance successive blanks simultaneously with the shaping and ironing operations.

EDWIN H. NEWTON.
